Robert H. Langdon and Richard D. McWilliams,
Dallas, Tex.

Application September 14, 1953, Serial No. 26,788

Term of patent 14 years

(Cl. D7—7)

To all whom it may concern:

Be it known that we, Robert H. Langdon and Richard D. McWilliams, both citizens of the United States, and both residing at Dallas, in the county of Dallas and State of Texas, have invented a new, original, and ornamental Design for a Shoe, of which the following is a specification, reference being had to the accompanying drawing, forming a part thereof.

Figure 1 is a side elevation of a shoe, showing our new design.

Figure 2 is a top plan view of the shoe shown in Figure 1, with the ankle tie untied.

Figure 3 is a rear elevation thereof with the toe tie omitted and portions of the ankle tie broken away for convenience of illustration, and

Figure 4 is a front elevation.

We claim:

The ornamental design for a shoe, substantially as shown and described.
